UNITED STATES PATENT OFFICE.

WILLIAM MUSHET AND ROBERT MUSHET, OF DALKEITH, SCOTLAND,
ASSIGNORS TO JORDAN L. MOTT, OF MOTT HAVEN, NEW YORK.

DESIGN FOR GARDEN-CHAIRS.

Specification forming part of Design No. 5,831, dated April 30, 1872.

CASE G.

Specification describing a new and original Design for Garden-Chairs, invented by WILLIAM MUSHET and ROBERT MUSHET, of Dalkeith, in the county of Edinburgh, in Scotland.

The nature of our design is fully illustrated in the accompanying photographic illustration, to which reference is made.

We claim—

1. The design of the top or crown a of the center of the back, as shown.
2. We also claim the design of the part b of the center back, as shown.
3. We also claim the design of the panel c in the center back, as shown.
4. We also claim the design of the panel d in the center back, as shown.
5. We also claim the design of the end-back frames e, as shown.
6. We also claim the design of the end pieces f, as shown.

7. We also claim the design of the legs g, as shown.
8. We also claim the design of the end pieces h, as shown.
9. We also claim the design of the seat-front, as shown.
10. We also claim the entire design for garden-chairs, comprising the several designus above specified.

The above specification of our invention signed by us this 12th day of January, 1872.

W. MUSHET.
R. MUSHET.
